GOVERNOR FOR PRIME MOVERS

Irving M. Crafts, Portland, and Charles B. Taylor,
Middletown, Conn., assignors to The Pickering
Governor Company, Portland, Conn., a corpo-
ration of Connecticut

Application August 17, 1940, Serial No. 353,098

25 Claims. (Cl. 264—3)

Our invention relates to the class of devices which are employed for regulating the speed of power generating mechanisms, and an object of the invention, among others, is to provide a mechanism of this type that may be regulated to maintain uniform speeds under varying conditions and that shall be particularly effective in the production of maximum results for which it is contemplated.

One form of a governor embodying the invention and in the construction and use of which the objects herein set out, as well as others, may be attained is illustrated in the accompanying drawings, in which—

Figure 1 is a diagrammatic sectional view in perspective of the lower part of our improved governor.

Figure 2 is a similar view of the upper part of said governor.

In the accompanying drawings the mechanism is shown in the position it will assume when the engine or prime mover is running at its normal speed, the numeral 5 denoting a fly-ball head rotatably mounted and driven by the engine through a torsionally flexible drive 6 of any well known character. In the arrangement herein shown the shaft of the torsionally flexible drive has a gear 7 secured to it at one end and its opposite end is connected through the flexible element of said drive with a governor shaft 8. Fly-weights 9 are pivotally mounted on the head in a manner common to governor construction and are yieldingly held in a lowered position by a spring 10 extending between said weights. Radial movement of these weights causes a main pilot valve 11 to move up or down in response to speed changes in the engine.

The gear 7 may be connected directly with the engine or it may be connected in the manner herein shown in which said connection is made through a gear oil pump comprising pump gears 12—13, the former connected by a transmission shaft 14 and a gear 15 with the gear 7, and the latter being secured to a pump driving shaft 16 having a gear 17 driven by power derived from the engine. This pump is the source of energy for operating power pistons to be hereinafter described, said pump comprising a reservoir 18 from which oil or other liquid is drawn in to the chamber containing the pump gears 12—13 past a ball check valve 19, said liquid being discharged under pressure past a ball check valve 20 into a pressure accumulating chamber 21. Ball check valves 22—23 are arranged in the valve chambers 24—25 to function as automatic

reversing valves to permit rotation of the pump in the opposite direction and flow of liquid through passages 26—26' to the pressure accumulating chamber 21 in a manner which will be readily seen.

A spring loaded piston 27 in the pressure chamber 21 acts as a relief valve to discharge oil through a relief port 28 into the reservoir 18 when the pressure in the chamber 21 becomes excessive. This chamber thus holds a sufficient quantity of oil under pressure to meet momentary demands of the governor which may be in excess of the instantaneous rate of pump output.

The main pilot valve 11 has lands 29—30 operating to cover and uncover ports 31—32 and 33—34 in a stabilizing bushing 35, in a valve chamber in which the main pilot valve 11 is located and has reciprocating and rotating movement. The stabilizing bushing 35 is located within a speed droop bushing 36, said bushings constituting the lower portion of a main valve system. A main oil supply passage 31 leads from the pressure chamber 21 and opens against the speed droop bushing 36 in a bushing chamber 38. A branch 39 from said oil supply passage leads into an annular bushing chamber 38' extending around the bushing 36 at the upper part thereof. Passages 40—41 for oil lead from the upper sides of chambers containing power pistons, to be hereinafter described, into an annular bushing chamber 38'', and passages 42—43 lead from the bottoms of said chambers on the opposite sides of said power pistons into an annular bushing chamber 38''' in said bushing 36. A throttle power piston 44 is located in a power piston chamber 45 and is connected by a piston rod 46 and a link connection with a throttle lever 47 secured to the throttle shaft 48 rotatably mounted in the support for the mechanism being described. The throttle lever 47 has a roller 49 riding in a slot in a connecting lever 50 pivotally mounted on a supporting sector 51 which is pivotally mounted by a pivot 52 on a stationary support. The lever 50 has a roller 53 riding in a slot in a lever 54 pivotally mounted on the upper end of a piston rod 55 of a compensator piston 56 mounted in a compensator piston chamber 57 formed in the governor structure.

The lever 54 carries a trunnion pin mounting a roller 58 which rides upon a disk 59 secured to the upper end of a compensator valve 60 screw threadedly engaged with the shank 61 of the stabilizing bushing 35. This compensator valve 60 controls ports 62—63 in the outer valve or speed

droop bushing 36, said ports opening to passages 64—65 leading into a valve chamber 66 containing an immovable timing member 67 with restricted channels 67' for flow of oil to and from the compensator piston chamber 57 to time the movement of the compensator piston 56. This timing member is of cylindrical form with an enlarged central part to fit the chamber 66 and with ends reduced in size to form the channels 67' which restrict the amount of flow to and from the chamber 57 and thus regulate the rate of movement of the compensator piston 56. The speed droop bushing 36 is supported at its upper end by means of a disk 68 having an arm 69 carrying a roller 70 riding in a slot in a sliding bearing 71 mounted on a pivot 72 carried by a bell crank lever presently to be described. The bearing 71 has an arm 73 having a slot 74 which receives a roller 75 mounted on the side of a second throttle lever 76 secured to the throttle shaft 48. One end of the lever 76 has a link connection with the piston rod 77 of a second power piston 78 mounted in a piston chamber in the governor structure. This piston chamber 79 is connected by the passages 41—43 with the bushing chambers 38" and 38'', respectively, as hereinbefore described.

The bell crank lever hereinbefore referred to comprises an arm 80 and a bar 81 mounted on a pin 80' fixedly secured in the governor frame, said arm carrying the pivot 72 for the sliding bearing 71 hereinbefore referred to and the bar 81 having a slot 82 which receives a roller 83 mounted on a stud on the side of a threaded adjusting sleeve 84. An adjusting spindle 85 is rotatably mounted in a fixed bearing and threadedly engages within the sleeve 84 and carries a knob 86 for hand manipulation for the purpose of turning the spindle and vertically adjusting the position of the sleeve 84. The shank 61 of the stabilizing bushing 35 has an adjusting rod 87 engaged therewith and having an adjusting knob 88 by means of which said shank may be turned to adjust the position of the stabilizing bushing 35 relatively to the compensator valve 60 for setting the speed adjustment. The rod 87 is connected by a gear train 89 with a dial 90. This dial is adjustably mounted relatively to the rest of the mechanism and may readily be released by backing off a clamping collar 91. A zero mark is provided on the dial to indicate its normal position in a manner common to structures of this type.

The sector 51 may be adjusted on its supporting pivot 52 by means of an adjusting screw 92 mounted in the governor frame and screw threadedly engaged with a threaded edge of the sector for changing the positions of the points of engagement between the throttle lever 47 and the lever 50 and also between said lever 50 and the lever 54. The end of the adjusting screw may be provided with a head 93 to receive a wrench as a means for rotating the screw to provide for said adjustment.

It will be noted that the mouths of the several ports in the bushings 35 and 36 are enlarged to provide for the necessary movements of said bushings for the purposes required of the structure.

Governor operation

The operation of the governor is as follows, it being assumed that the parts are in position with the prime mover or engine running at its normal speed.

Upon an increase of speed the fly weights 9 move outward causing the main pilot valve 11 to 75

move downward uncovering the ports 31—33 and 32—34 in the stabilizing bushing 35. This admits oil from the main oil passage 37 and permits it to flow through the ports 31—33 to the under side of the throttle power pistons 44—78, forcing these pistons upwardly. Oil on the upper sides of said pistons is discharged through the passages 40—41 and the ports 32—34 in the bushing 35 and registering ports in the bushing 36 to the upper side of the chamber containing the main pilot valve 11 and through an orifice 94 into a chamber 95 and thence by way of a port 96 and a passage 97 back to the pump reservoir 18, the portion of said passage next to the port 96 only being shown. The power pistons 44 and 78 being directly connected to the throttle levers 47 and 76 cause the throttle shaft 48 to rotate in a direction to close the engine throttle. The degree of throttle shaft movement is limited and stabilized by relay action as follows:

Stabilizing relay

Upward movement of the power piston 44 and the outer end of the throttle lever 47 rotates the connecting lever 50 on its pivot on the sector 51, and the movement of the lever 50 is thus transmitted to the lever 54. The outer end of the lever 54 is thus moved downwardly pressing the roller 58 against the disk 59 thereby moving the valve system comprising the compensator valve 60 and the stabilizing bushing 35 downwardly. Thus upward movement of the power piston 44 in effecting downward movement of the valve system also causes a similar movement of the ports 31—33 which were opened by the downward movement of the main pilot valve hereinbefore mentioned. The power piston 44 will continue to move upwardly until said ports 31—35, originally opened by change of speed, are again closed. This will prevent further movement of the power pistons and consequently will stop rotation of the throttle shaft 48 and the degree of movement of said shaft produced by a given degree of speed change is therefore determined by the proportions of the relay. Movement of the shaft 48 to close the throttle causes a reduction in the speed of the engine to some value below the original increase and this reduction in speed causes the fly weights to reverse their original movement and thereby move the main pilot valve 11 upward. This return movement of said pilot valve would cause the power pistons to reverse their movements and again open the throttle but this is prevented by means of a dash pot compensator acting as follows:

Dash pot compensator

The compensator valve 60 controls the flow of oil through the ports 62—63 located in the upper end of the speed droop bushing 36. When the valve system was moved downwardly as hereinbefore described by action of the roller 58 said valve uncovered the ports 62—63, permitting the oil pressure in the branch 39 of the oil passage to flow through the passage 64 past the timing member 67 into the chamber underneath the compensator piston 56 and the oil on the upper side of said piston is discharged past the timing valve through the passage 65 over the upper end of the valve 60 and thence to the oil reservoir 18 through a passage arranged in any ordinary manner but not shown. The piston 56 is thus caused to move upwardly rotating the lever 54 about its sliding bearing or roller 53 on the connecting lever 50. The roller 58 is thereby caused

to move upward and this permits the valve system to rise. It should be noted that oil flowing to and from the piston 56 must pass through the restricted channels formed by the reduced ends of the timing member 67 and between said reduced ends and the walls of the chamber 66 thereby controlling the rate of movement of said piston. Therefore as the main pilot valve 11 is moving towards its original position, as already described, the stabilizing bushing 35 is also moving in the same direction and approximately at the same rate. As the piston 56 will continue to move until the valve ports 62-63 are again covered by the compensator valve 60 the final point of stability for the valve system is identical with its original position. This is so because the position of the speed droop bushing 36 which contains the ports 62-63 is fixed when the governor is to be used for isochronous regulation and as hereinbefore described.

Speed droop

The term "speed droop" is used to denote the change in speed that occurs when the engine is running under no-load conditions as compared with the speed under full-load conditions. This speed droop mechanism acts as follows:

The speed droop bushing 36 is supported as hereinbefore stated by a disk 68 having an arm 69 containing a roller 70 located in a slot in an adjustably mounted support for said disk. This support comprises the bearing 71 hereinbefore mentioned which is in the form of a block rigidly supported by the arm 73 through the medium of a sleeve mounted on the pivot 72, the block and bearing 71 therefore directly supporting said bushing. This support for the disk 68 being mounted on the pivot 72 of the bell crank lever comprising the arm 80 and bar 81 enables the position of the support to be adjusted for a purpose to be presently described, in this movement the support having a sliding movement relatively to the lever 76 and arm 69, this sliding movement taking place upon the rollers 70 and 75. It is to be noted that a spring is interposed between the disks 59 and 68, the force of the spring being exerted in opposite directions on said disks. The bell crank lever is rotatably mounted on the pin 80 secured to the frame of the governor mechanism. Pivotal movement on said pin is for purposes of adjustment which is effected by vertical movement of the adjusting sleeve 84 on the threaded adjusting spindle 85, thereby carrying the sliding bar 81 up or down when the adjusting spindle 85 is rotated as by means of the fluted knob 86. Therefore if the throttle lever 76 is rotated by vertical movement of the power piston 78 a similar rotation is imparted to the arm 73. When the position of the bell crank lever is adjusted such that the center line of the pivot 72 is coincident with the center line of the pivot of the roller 70 rotation of the arm 73 will impart no movement to the speed droop bushing 36. If, however, the bell crank lever is adjusted to a position to place the bearing 72 out of line with the sliding bearing 73 then vertical movement will be imparted to the bushing 36 as the power piston 78 is moved. The mechanism is so constructed that when the piston moves toward throttle closing position due to load reduction on the engine the bushing 36 is moved in a downward direction. The positions of the ports 62-63 are thus moved downward and the point of stabilization of the valve system is thereby set at a higher speed position. This

mechanism is for the purpose of permitting speed droop by the action of the governor to such extent as may be desired.

Speed adjustment

5 The speed at which the governor will regulate the engine may be adjusted as follows:

The relative spacing between the compensator valve 60 and the stabilizing bushing 36 may be adjusted by means of the threaded screw on the shank 61 of said bushing. By thus moving said bushing up or down relatively to the fixed ports 62-63 the neutral position of the main pilot valve 11 is similarly moved up or down. Consequently the fly-ball element must rotate slower or faster to bring the valve 11 to the neutral position. Said shank containing the threaded screw may be rotated by means of the rod 87 to which the adjusting knob 88 is attached. The indicating dial 90 will denote the setting of speed adjustment.

Adjustable relay

In the description heretofore given it is set out that the proportions of relay determine the degree of throttle movement produced by a given degree of speed change. To secure the best operation from the standpoint of stability it is desirable to be able to adjust these proportions to suit individual operating conditions peculiar to engine characteristics. This adjustment may be obtained as follows:

25 The connecting lever 50 is pivotally mounted on the sector 51 as before described and the sector is mounted on the pivot 52 and may be rotated by means of the adjusting screw 92. It will therefore be seen that if the sector is rotated so that the point for the pivot of the connecting lever 50 is moved toward the sliding roller 49, the effective radius of the lever 50 from its pivot to the sliding roller 49 is shortened. Thus the throttle lever 47 and consequently the throttle shaft 48 must move a lesser distance to produce the same amount of movement of the roller 49 to effect closure of the ports 31-32. By this means it is possible to secure the proper amount of power piston or throttle movement to produce the most stable action. When the final adjustment is obtained a lock nut 98 holds the sector rigidly in that position and a pointer 99 may be employed to indicate the setting of adjustment. Thus provision is made in this construction to vary the proportions of the relay mechanism.

35 In accordance with the provisions of the patent statutes we have described the principles of operation of our invention, together with the device which we now consider to represent the best embodiment thereof; but we desire to have it understood that the device shown is only illustrative and that the invention may be carried out by other means and applied to uses other than those above set out.

We claim:

45 1. A governor mechanism including a motor driven centrifugally operated member, a main valve member operatively connected with said centrifugally operated member, a ported stabilizing member within which said main valve member is located, a piston located in a piston chamber, passages opening from said chamber on opposite sides of said piston, the ends of said passages opposite said chamber being located for opening and closing by said main valve member, a throttle operating lever operatively connected with said piston, a pivotally mounted

lever connected at one end with said throttle operating lever, an operative connection between the opposite end of said pivotally mounted lever and said stabilizing member for movement of the latter simultaneously with and in the same direction as that of movement of said main valve member and means for changing the point of connection between said levers to vary the amount of movement of said stabilizing member.

2. A governor mechanism including a motor driven centrifugally operated member, a main valve member operatively connected with said centrifugally operated member, a ported stabilizing member within which said main valve member is located, a piston located in a piston chamber, passages opening from said chamber on opposite sides of said piston, the ends of said passages opposite said chamber being located for opening and closing by said main valve member, a throttle operating lever operatively connected with said piston, a pivotally mounted lever connected at one end with said throttle operating lever, an adjustable movable mount for said pivotally mounted lever to change its point of connection with said throttle operating lever, and an operative connection between the opposite end of said pivotally mounted lever and said stabilizing member for operation of the latter simultaneously with and in the same direction as that of movement of said main valve.

3. A governor mechanism including a motor driven centrifugally operated member, a main valve member operatively connected with said centrifugally operated member, a ported stabilizing member within which said main valve member is located, a piston located in a piston chamber, passages opening from said chamber on opposite sides of said piston, the ends of said passages opposite said chamber being located for opening and closing by said main valve member, a throttle operating lever operatively connected with said piston, a pivotally mounted sector, a connecting lever pivotally mounted on said sector and engaged at one end with said throttle operating lever, and an operative connection between the opposite end of said connecting lever and said stabilizing member for operation of the latter simultaneously with and in the same direction as that of movement of said main valve.

4. A governor mechanism including a motor driven centrifugally operated member, a main valve member operatively connected with said centrifugally operated member, a ported stabilizing member within which said valve member is located, a piston located in a piston chamber, passages opening from said chamber on opposite sides of said piston, the ends of said passages opposite said chamber being located for control by said valve member, a throttle operating lever operatively connected with said piston, a pivotally mounted sector, a connecting lever pivotally mounted on said sector and having a slotted engagement at one end with said throttle operating lever, a stabilizing lever, a slotted engagement between said stabilizing lever and the opposite end of said connecting lever, and an operative connection between said stabilizing lever and said stabilizing member for operation of the latter simultaneously with and in the same direction as that of movement of said valve.

5. A governor mechanism including a motor driven centrifugally operated member, a main valve member operatively connected with said centrifugally operated member, a ported stabiliz-

ing member within which said valve member is located, a shank extending from said stabilizing member, a piston located in a piston chamber, passages opening from said chamber on opposite sides of said piston, the ends of said passages opposite said chamber being located for control by said valve member, a throttle operating lever operatively connected with said piston, a stabilizing lever, a pivotally mounted sector, a connecting lever having slotted engagement at its opposite ends with said throttle operating lever and with said stabilizing lever to permit movement of said connecting lever by said sector to change the points of engagement between said connecting lever and said throttle and stabilizing levers, a disk secured to the shank of said stabilizing member, and a connection between said stabilizing lever and said disk for operation of said stabilizing member simultaneously with and in the same direction as that of movement of said main valve.

6. A governor mechanism including a motor driven centrifugally operated member, a main valve operatively connected with said centrifugally operated member, a stabilizing bushing within which said valve is located, a bushing chamber within which said bushing is located, a compensator valve located in said bushing chamber, an operative connection between said stabilizing bushing and compensator valve, a power piston chamber, a power piston in said power piston chamber, passages opening from said power piston chamber on opposite sides of said piston, the ends of said passages opposite said power piston chamber being controlled by said main valve, a throttle member operatively connected with said piston, a stabilizing lever having a support at one end operatively connected with said throttle member, a compensator piston supporting the opposite end of said stabilizing lever, a controlling valve for said compensator piston, passages communicating at one end with said controlling valve and with their opposite ends located for control by said compensator valve, and an operative connection between said stabilizing lever and said compensator valve.

7. A governor mechanism including a motor driven centrifugally operated member, a main valve operatively connected with said centrifugally operated member, a stabilizing bushing within which said valve is located, a bushing chamber within which said bushing is located, a compensator valve in said bushing chamber, an operative adjustable connection between said stabilizing bushing and compensator valve, a power piston, a power piston chamber for said power piston, passages opening from said power piston chamber on opposite sides of said power piston, the ends of said passages opposite said power piston chamber being controlled by said main valve, a throttle member operatively connected with said power piston, a stabilizing lever having a support at one end operatively connected with said throttle member, a compensator piston supporting the opposite end of said stabilizing lever, a compensator piston chamber for said compensator piston, passages communicating at one end with said compensator piston chamber and with their opposite ends located for control by said compensator valve, and an operative connection between said stabilizing lever and said compensator valve.

8. A governor mechanism including a motor driven centrifugally operated member, a main

valve operatively connected with said centrifugally operated member, a stabilizing bushing within which said valve is located, a bushing chamber in which said bushing is located, a compensator valve located in said bushing chamber, a shank on said bushing extending through and screw threadedly engaged with said compensator valve, a power piston chamber, a power piston in said power piston chamber, passages opening from said power piston chamber on opposite sides of said piston, the ends of said passages opposite said power piston chamber being controlled by said main valve, a throttle member operatively connected with said power piston, a stabilizing lever having a support at one end operatively connected with said throttle member, a compensator piston supporting the opposite end of said stabilizing lever, a compensator piston chamber for said compensator piston, passages communicating at one end with said compensator piston chamber and with their opposite ends located for control by said compensator valve, and an operative connection between said stabilizing lever and said compensator valve.

9. A governor mechanism including a motor driven centrifugally operated member, a main valve operatively connected with said centrifugally operated member, a stabilizing bushing within which said valve is located, a bushing chamber in which said bushing is located, a compensator valve in said bushing chamber, a shank extending from said stabilizing bushing through and screw threadedly engaged with said compensator valve, a power piston chamber, a power piston in said power piston chamber, passages opening from said power piston chamber on opposite sides of said piston, the ends of said passages opposite said power piston chamber being controlled by said main valve, a throttle member operatively connected with said piston, a stabilizing lever having a support at one end operatively connected with said throttle member, a compensator piston supporting the opposite end of said stabilizing lever, a compensator piston chamber for said compensator piston, passages communicating at one end with said compensator piston chamber and with their opposite ends located for control by said compensator valve, a disk secured to the shank of said stabilizing bushing, and means on said stabilizing lever engaged with said disk to operate the compensator valve and stabilizing bushing.

10. A governor mechanism including a motor driven centrifugally operated member, a main valve operatively connected with said centrifugally operated member, a stabilizing bushing within which said valve is located, a bushing chamber in which said bushing is located, a compensator valve in said bushing chamber, an operative connection between said stabilizing bushing and compensator valve, a power piston chamber, a power piston in said power piston chamber, passages opening from said power piston chamber on opposite sides of said piston, the ends of said passages opposite said power piston chamber being controlled by said main valve, a throttle member operatively connected with said piston, a stabilizing lever having a support at one end operatively connected with said piston, a compensator piston supporting the opposite end of said stabilizing lever, a compensator piston chamber for said compensator piston, passages communicating at one end with said compensator piston chamber and with their opposite ends located for control by said compensator

valve, a timing valve for controlling admission of pressure to the chamber of said compensator piston, and an operative connection between said stabilizing lever and said compensator valve.

5 11. A governor mechanism including a motor driven centrifugally operated member, a main valve operatively connected with said centrifugally operated member, a ported stabilizing member having its ports controlled by said main valve, means for actuating said stabilizing member, a ported speed droop member having flow of fluid through its ports controlled by said main valve, a power piston, a chamber for said piston, passages opening from said chamber on opposite sides of said piston and communicating with the ports of said speed droop member, a throttle member operatively connected with said piston, and an operative connection included in the means for actuating the stabilizing member and extending between said throttle member and said speed droop member.

10 12. A governor mechanism including a motor driven centrifugally operated member, a main valve operatively connected with said member, a ported stabilizing member having its ports controlled by said main valve, means for actuating said stabilizing member, a ported speed droop bushing within which said main valve is located, a power piston, a chamber for said piston, passages opening from said chamber on opposite sides of said piston and communicating with the ports of said speed droop member, a throttle member operatively connected with said piston, and an operative connection included in the means for actuating the stabilizing member and extending between said throttle member and said speed droop member.

15 13. A governor mechanism including a motor driven centrifugally operated member, a main valve operatively connected with said centrifugally operated member, a ported stabilizing bushing having its ports controlled by said main valve, a ported speed droop bushing within which said stabilizing bushing is located, a power piston, a chamber for said piston, passages opening from said chamber on opposite sides of said piston and communicating with the ports of said speed droop bushing, a throttle member operatively connected with said piston, an operative connection between said throttle member and said speed droop bushing, and an operative connection between said throttle member and said stabilizing bushing.

20 14. A governor mechanism including a motor driven centrifugally operated member, a main valve operatively connected with said centrifugally operated member, a ported stabilizing bushing within which said main valve is located, a ported speed droop bushing within which said stabilizing bushing is located, the ports in said bushings being adapted to register one with another, a power piston, a chamber for said piston, passages opening from said chamber on opposite sides of said piston and communicating with the ports of said speed droop member, a throttle member operatively connected with said piston, an operative connection between said throttle member and said speed droop bushing, and an operative connection between said throttle member and said stabilizing bushing.

25 15. A governor mechanism including a motor driven centrifugally operated member, a main valve operatively connected with said centrifugally operated member, a ported stabilizing bushing within which said main valve is located, a

ported speed droop bushing within which said stabilizing bushing is located, the ports in said bushings being adapted to register one with another, a power piston, a chamber for said piston, passages opening from said chamber on opposite sides of said piston and communicating with the ports of said speed droop bushing, a throttle member operatively connected with said piston, an operative connection between said throttle member and said speed droop bushing, said connection including a speed droop bushing support, a swinging support, a connecting arm pivotally mounted on said swinging support and slidably engaged at one end with said speed droop bushing support and at its opposite end operatively connected with said throttle member, and an operative connection between said throttle member and said stabilizing bushing.

16. A governor mechanism including a motor driven centrifugally operated member, a main valve operatively connected with said centrifugally operated member, a ported stabilizing bushing within which said main valve is located, a ported speed droop bushing within which said stabilizing bushing is located, the ports in said bushings being adapted to register one with another, a power piston, a chamber for said piston, passages opening from said chamber on opposite sides of said piston and communicating with the ports of said speed droop bushing, a throttle member operatively connected with said piston, an operative connection between said throttle member and said speed droop bushing, said connection including a speed droop bushing support, a bell crank lever mounted on a fixed pivot, a connecting arm pivotally mounted on said bell crank lever and slidably engaged at one end with said speed droop bushing support and at its opposite end operatively connected with said throttle member, means for adjusting the bell crank lever on its support, and an operative connection between said throttle member and said stabilizing bushing.

17. A governor mechanism including a motor driven centrifugally operated member, a main valve operatively connected with said centrifugally operated member, a ported stabilizing bushing within which said main valve is located, a ported speed droop bushing within which said stabilizing bushing is located, the ports in said bushings being adapted to register one with another, a power piston, a chamber for said piston, passages opening from said chamber on opposite sides of said piston and communicating with the ports of said speed droop bushing, a throttle member operatively connected with said piston, an operative connection between said throttle member and said speed droop bushing, said connection including a speed droop bushing support, a bell crank lever mounted on a fixed pivot and comprising a supporting arm and an adjusting bar, an adjusting sleeve having slotted engagement with said bar, an adjusting spindle screw threadedly engaged with said sleeve, means for turning said spindle to effect said adjustment, and an operative connection between said throttle member and said stabilizing bushing, said supporting arm being operatively connected with said throttle member.

18. A governor mechanism including speed controlled governor means, a main valve member operatively connected with said means, a ported stabilizing member within which said main valve is located, a piston located in a piston chamber, passages opening from said chamber on oppo-

site sides of said piston, the ends of said passages opposite said chamber being located for opening and closing by said main valve member, a throttle operating lever operatively connected with said piston, a pivotally mounted lever connected at one end with said throttle operating lever, an adjustable movable mount for said pivotally mounted lever to change its point of connection with said throttle operating lever, and an operative connection between the opposite end of said pivotally mounted lever and said stabilizing member for operation of the latter simultaneously with and in the same direction as that of movement of said main valve.

19. A governor mechanism including a motor driven centrifugally operated member, a main valve member operatively connected with said centrifugally operated member, a ported stabilizing member within which said main valve member is located, a piston located in a piston chamber, passages opening from said chamber on opposite sides of said piston, the ends of said passages opposite said chamber being located for opening and closing by said main valve member, a throttle operating lever operatively connected with said piston, a pivotally mounted lever connected at one end with said throttle operating lever, an adjustable movable mount for said pivotally mounted lever to change its point of connection with said throttle operating lever, an operative connection between the opposite end of said pivotally mounted lever and said stabilizing member for operation of the latter simultaneously with and in the same direction as that of movement of said main valve, and a speed droop member operatively connected with said throttle operating lever for operation simultaneously therewith.

20. A governor mechanism including speed controlled governor means, a valve system comprising a valve member and a stabilizing member located one within the other and one of which is connected with said governor means for movement thereby to open and close ports in the other of said members, a valve chamber within which said stabilizing member is located, a compensator valve located in said valve chamber, a piston located in a piston chamber, passages opening from said piston chamber on opposite sides of said piston, the ends of said passages opposite said piston chamber being located for opening and closing by said valve member, a throttle member operatively connected with said piston, and an operative connection between said throttle member and said compensator valve and said stabilizing member for operation of said last mentioned valve and member.

21. A governor mechanism including speed controlled governor means, a valve system comprising a valve member and a stabilizing member located one within the other and one of which is connected with said governor means for movement thereby to open and close ports in the other of said members, a valve chamber within which said stabilizing member is located, a compensator valve located in said valve chamber and operatively connected with said stabilizing member, a speed droop bushing located in said valve chamber, means for operating said stabilizing member, a piston located in a piston chamber, passages opening from said piston chamber on opposite sides of said piston, the ends of said passages opposite said piston chamber being located for opening and closing by said valve member, a throttle member operatively connected

with said piston, and an operative connection between said throttle member and said compensator valve and said stabilizing member for operation of said last mentioned valve and member by said throttle member.

22. A governor mechanism including speed controlled governor means, a valve system comprising a valve member and a stabilizing member located one within the other and one of which is connected with the governor means for movement thereby to open and close ports in the other of said members, a valve chamber within which said stabilizing member is located, a compensator valve located in the end of said chamber opposite said stabilizing member, a shank on said stabilizing member extending through said compensator valve, means for adjusting the relative positions of said stabilizing member and said compensator valve, a piston located in a piston chamber, passages opening from said piston chamber on opposite sides of said piston, the ends of said passages opposite said piston chamber being located for opening and closing by said valve member, a throttle member operatively connected with said piston, and an operative connection between said throttle member and said compensator valve and said stabilizing member for operation of the last mentioned valve and member by said throttle member.

23. A governor mechanism including speed controlled governor means, a valve system comprising a valve member and a stabilizing member located one within the other and one of which is connected with said governor means for engagement thereby to open and close ports in the other of said members, a valve chamber within which said stabilizing member is located, a compensator valve located in the end of said valve chamber opposite said stabilizing member, a shank from said stabilizing member extending through said compensator valve and threadedly connected therewith, means for turning said shank to adjust the relative positions of said stabilizing member and compensator valve, a piston located in a piston chamber, passages opening from said piston chamber on opposite sides

of said piston, the ends of said passages opposite said piston chamber being located for opening and closing by said valve member, a throttle member operatively connected with said piston, and an operative connection between said throttle member and said compensator valve and said stabilizing member for operation of said last mentioned valve and member by said throttle member.

24. A governor mechanism including a motor driven centrifugally operated member, a main valve operatively connected with said centrifugally operated member, a ported stabilizing member having its ports controlled by said main valve, means for actuating said stabilizing member, a ported speed droop member having flow of fluid through its ports controlled by said main valve, a power piston, a chamber for said piston, passages opening from said chamber on opposite sides of said piston and communicating with the ports of said speed droop member, a throttle member operatively connected with said piston, and an operative connection between said throttle member and said speed droop member, said connection including means for adjusting the amount of relative movement between said throttle member and said speed droop member.

25. A governor mechanism including speed controlled governor means, a main valve operatively connected with said governor means, a ported speed droop member having flow of fluid through its ports controlled by said main valve, a power piston, a chamber for said piston, passages opening from said chamber on opposite sides of said piston and communicating with the ports of said speed droop member, a throttle member operatively connected with said piston, and an operative connection between said throttle member and said speed droop member, said connection including means for changing the point of engagement of said throttle member and said connection to vary the amount of relative movement between said throttle member and said connection.
